UNITED STATES PATENT OFFICE.

HARRY R. DECKER, OF HOUSTON, TEXAS.

MECHANISM FOR DRILLING WELLS.

No. 920,548.

Specification of Letters Patent.

Patented May 4, 1909.

Application filed October 12, 1906, Serial No. 338,627. Renewed September 17, 1908. Serial No. 458,502.

To all whom it may concern:

Be it known that I, HARRY R. DECKER, a citizen of the United States, residing at Houston, in the county of Harris and State 5 of Texas, have invented certain new and useful Improvements in Mechanism for Drilling Wells, of which the following is a specification.

My invention relates to machinery used in 10 drilling oil, water and gas wells by what is known as the rotary process, and consists in providing a rotary table for rotating the drill stem in which a telescoping cylindrical structure is slidably mounted in the opening in the 15 table with the drill stem clamping means mounted on said telescoping structure so that the drill stem may be reciprocated vertically when it is desired to force through a hard formation, familiarly known as "punching gumbo" without loosening the rotary pipe grips.

The telescoping structure and its connections are so constructed that when desired it may be held stationary and locked to the tubular drill stem below a coupling or collar while a clamping structure secured to the rotary table is secured to the stem above the coupling or collar and when the table is rotated the upper length of pipe may either be 30 screwed into or out of the collar.

Heretofore in rotary tables whenever a collar or coupling is passing through the clamps it has been necessary to stop the drilling and open the clamping jaws so as to engage the coupling and after the coupling has 35 passed on close the jaws together on the adjacent length of tubular stem.

In my improved table the jaws may be raised above the coupling and secured to the 40 length of tubing above the coupling without resetting them on the coupling and the drilling proceed without interruption to the next coupling.

When the telescoping structure is in any 45 position high or low the device may be used as an ordinary rotary drilling machine.

The description of the construction and operation of my improved drilling machine will be described in detail hereinafter and 50 illustrated in the accompanying drawings in which--

Figure 1 is a vertical sectional view showing my improved device in operation as a drilling machine, Fig. 2, a similar view showing the machine in position for screwing or 55 unscrewing a length of tubing, Fig. 3, an-

other view showing the telescoping structure extended, Fig. 4, a top plan view of the table and telescoping structure, Fig. 5, a cross section of the telescoping structure, 60 Fig. 6, a detail view of one of the jaws connected with the table, Fig. 7, an enlarged view in cross-section of one of the links of the chain used in connection with the clamping jaws, and Fig. 8 a fragmental view partly in 65 section showing the bevel gearing.

In the drawings similar reference characters indicate corresponding parts throughout the several views.

1 indicates a suitable foundation of timbers on which is mounted the bed plate 2 of my improved rotary table, said bed plate being provided with a circular raceway 3 in its upper surface in which are mounted the anti-friction bearing devices 4, shown in the drawings as conically-shaped cylinders but any other form of bearings either anti-frictional or not may be substituted as desired.

Seated on the bed plate 2 and the bearings 4 is the master wheel 5 having a raceway 6 in its bottom surface to receive said bearings 4 and held in position by means of angular arms 7 secured to bed plate 2 and loosely mounted in circumferential groove 8 in the side of said master wheel.

9 indicates a cylindrical extension from the inner portion of the wheel 5 that bears against the inner surface of the bed plate 2 to act as a guide for the master wheel in the bed plate and also serves to extend the opening 90 in the master wheel and to guide the telescoping structure hereinafter described.

A beveled gear face 10 is formed on the side of the wheel with which meshes a beveled pinion 11 keyed to shaft 12 that is 95 driven by any suitable power.

13 indicates ears on the upper face of the master wheel and adjacent to its outer edge, said ears being formed with slots 14 for the purpose hereinafter stated.

15 represents a cylindrical tube slidably mounted in the opening 16 in the master wheel having a beveled flange 17 extending from its upper edge to seat in beveled depression 18 in the master wheel to limit the downward movement of the tube. The inner surface of the tube 15 is formed with guide-way grooves 15^a while the exterior of the tube is formed with other grooves 17^a to receive pins 19 slidably mounted in the master-wheel 5 having their inner ends beveled as shown at 19^a, said pins being held nor-

mally withdrawn into the master-wheel and from engagement with grooves 17^a by means of springs 20.

21 indicates screw plugs having tapered 5 lower ends 22 to bear against the beveled ends 19^a to project pins 19.

23 indicates another cylinder slidably mounted in cylinder 15 having longitudinal projections 23^a to fit into grooves 15^a in said 10 cylinder 15. The upper end of cylinder 23 is formed with a flat table extension 24 having its outer edge notched as shown at 25 to fit over ears 13. The outer surface of cylinder 23 is grooved as shown at 26 to receive 15 the ends of screws or pins 26^a secured in cylinder 15.

Secured to the upper side of table 24 are guides 27 on which are slidably mounted the frames 28 actuated by screw shafts 29. The 20 clamping jaws consist of shouldered cylinders 30 journaled in frames 28 and adapted to engage the drill stem 31.

It will be understood from the above description that when the telescoping tubes 15 and 23 are in their lowermost position, as shown in Fig. 1, so that notches 25 engage ears 13, power transmitted to the master wheel through shaft 12 and beveled pinion 11 will actuate said master-wheel and if the 30 jaws 30 are clamped in drill stem 31 that it will be rotated with the table.

It will be also understood that by raising the inner cylinder 23 and projecting the pins 19 into grooves 17^a the jaws 30 may be secured above a coupling ring 32 on drill stem 31 and as the drilling proceed the table will gradually settle until it resume its position as shown in Fig. 1, or if a stratum of gumbo, shale, or other resisting substance be encountered the drill stem with the cylinders 15 and 23 (comprising a telescoping structure) may be reciprocated so as to punch through said stratum without loosening the jaws.

45 33 indicates arms having hinged extensions 34 at their lower ends adapted to fit into slots 14 in ears 13 and with hinged jaws 35 secured to their upper ends having their ends formed to grip the drill stem 31. Ad- 50 jacent to the upper end of each arm 33 is formed claws 36 to receive one of the links of a chain 37 while on the upper side of each jaw is secured a post 38 around one of which the chain 37 is wound after securing to the 55 claws on one arm and then wound around the pipe and secured to the claws on the other arm. The purpose of this construction is to admit of the clamps giving to the slight vertical movement incident to the screwing and 60 unscrewing into and out of the coupling 32.

The links of chain 37 are preferably made of a soft material such as wrought iron and have secured transversely thereof pointed plates 39 that operate as biting points for 65 said links.

40 indicate hooks pivotally mounted in supporting lugs 41 integral with the bottom of bed plate 2 and operated by screw shafts 42 secured through the beams of frame 1. These hooks are swung under and engage 70 notches 15^b in the lower edge of the cylinder 15 when it is desired to use the machine for coupling or uncoupling lengths of the stem and operate to lift the telescoping structure so that the notches 25 are out of engagement 75 with the ears 13. The master wheel 5 may then be rotated independently of the telescoping structure, and by clamping the upper length of the stem by means of the arms 33 and their connections and securing the lower length of the stem and coupling to the telescoping structure by casting a chain 43 several times around the stem and coupling and securing one end to a projection 44 on one of the clamping frames 28 the lengths of pipe 80 may be screwed or unscrewed by turning the master wheel in the proper direction.

45 indicates an elevator of the conventional type and 49 links secured to said elevator and adapted to receive a hook connected 90 with a hoisting device (not shown) when it is desired to raise the drill stem.

I have shown and described a telescoping structure consisting of two coaxing cylinders but it will be apparent that the device will 95 operate with but a single cylinder or that more than two cylinders may be employed as well as only two and I do not, therefore, limit myself to the construction shown and described except where I have done so expressly in the claims.

It will also be apparent that other forms of clamps than those shown and described may be used with my machine so that, except where specifically limited by the claims, I do 105 not confine myself to the construction shown and described herein.

Having thus described my invention what I claim is—

1. A casing screwer consisting of a revolving table, a telescopic attachment carrying the clamping devices for holding one section of the casing stationary, means for revolving the table independently of the telescopic attachment, and means for imparting the rotation of the table to another section of the casing to turn it relatively to the first-mentioned section, substantially as shown and described.

2. In combination with a rotary table for 110 drilling wells, a telescoping structure operatively connected therewith and carrying the drill stem clamping devices, substantially as shown and described.

3. In combination with a rotary table for 115 drilling wells having a central opening for the drill stem, a tube slidably mounted in said opening, the drill stem clamping devices mounted on said tube, and operative connections between said table and tube to rotate 120

125

130

- them simultaneously, substantially as shown and described.
4. In combination with a rotary table for drilling wells having a central opening for the drill stem, a tube slidably mounted in said opening having a flat table-like structure on its upper end, the drill stem clamping devices mounted on said table-like structure, and operative connections between said rotary table and tube to rotate them simultaneously, substantially as shown and described.
5. In combination with a rotary table for drilling wells having a central opening for the drill stem, a tube slidably mounted in said opening having its upper end extended horizontally to form a table having notches in its edge, the drill stem clamping devices mounted on said table, and upwardly projecting ears on the rotary table to engage the notches in the table aforesaid, substantially as shown and described.
6. In combination with a rotary table for drilling wells having a central opening for the drill stem, a tube slidably mounted in said opening having its inner surface longitudinally grooved, a second tube mounted inside of the first named tube having projections on its outer surface engaging the grooves in said first-named tube, the drill stem clamping devices mounted on said tube, and operative connections between said table and tubes to rotate them simultaneously, substantially as shown and described.
7. In combination with a rotary table for drilling wells having a central opening for the drill stem, a tube slidably mounted in said opening having its inner surface longitudinally grooved, a second tube mounted inside of the first named tube having projections on its outer surface engaging the grooves in said first-named tube, the inner tube having its upper end extended to form a table, the drill stem clamping devices mounted on said table, and operative connections between said rotary table and the table on the inner tube to rotate the tubes simultaneously with the rotary table, substantially as shown and described.
8. In combination with a rotary table for drilling wells having a central opening for the drill stem, a tube slidably mounted in said opening having its inner surface longitudinally grooved, a second tube mounted inside of the first-named tube having projections on its outer surface engaging the grooves in said first-named tube, the inner tube having its upper end extended to form a table having its outer edge notched, the drill stem clamping devices mounted on said table, and ears extending upwardly from said rotary table to engage the notches in the edge of the table aforesaid, substantially as shown and described.
9. In combination with a rotary table for drilling wells having a central opening, and a
- drill stem mounted in said opening consisting of lengths of pipe connected together by coupling rings, means to clamp one of said coupling rings and hold it stationary, arms removably secured to the rotary table, claws integral with said arms, jaws secured to said arms and engaging the lengths of pipe above the coupling ring, and a flexible element passed around said length of pipe and secured to the claws aforesaid, said arms and clamping elements operating to turn said length of pipe relative to the coupling ring, substantially as shown and described.
10. In combination with a rotary table for drilling wells having a central opening, and a drill stem mounted in said opening consisting of lengths of pipe connected together by coupling rings, means to clamp one of said coupling rings and hold it stationary, arms removably secured to the rotary table, claws integral with said arms, jaws secured to said arms and engaging the length of pipe above the coupling ring, a post extending upwardly from each jaw, and a flexible element passed around said length of pipe and one of said posts and secured to said claws, said arms and clamping elements operating to turn said length of pipe relative to the coupling ring, substantially as shown and described.
11. In combination with a rotary table for drilling wells having a central opening, and a drill stem mounted in said opening consisting of lengths of pipe connected together by coupling rings, a cylindrical telescoping structure mounted in the opening in the table and surrounding the drill stem, means secured to said telescoping structure to hold one of the coupling rings, means to hold said telescoping structure stationary, means secured to the rotary table to clamp the length of pipe above the coupling ring aforesaid, and means to rotate the table, substantially as shown and described.
12. In combination with a rotary table for drilling wells having a central opening, and a drill stem mounted in said opening consisting of lengths of pipe connected together by coupling rings, a cylindrical structure mounted in the opening in the table and surrounding the drill stem, a table formed integral with the cylindrical device, a flexible element passed around the coupling ring and suitably secured to the table, means to hold said cylindrical device stationary, means secured to the rotary table to clamp the length of pipe above the coupling ring aforesaid, and means to rotate said rotary table, substantially as shown and described.
13. In combination with a rotary table for drilling wells having a central opening, and a drill stem mounted in said opening consisting of lengths of pipe connected together by coupling rings, a cylindrical structure mounted in the opening in the table and

surrounding the drill stem, means to hold said cylindrical structure stationary, means secured to said cylindrical structure to hold one of the coupling rings, arms removably secured to the rotary table provided with means to clamp the length of pipe above the coupling ring aforesaid, and means to rotate said rotary table, substantially as shown and described.

10. 14. In combination with a rotary table for drilling wells having a central opening, and a drill stem mounted in said opening consisting of lengths of pipe connected together by coupling rings, a cylindrical structure mounted in the opening in the table and surrounding the drill stem, means to hold said cylindrical structure stationary, means secured to said cylindrical structure to hold one of the coupling rings, arms removably secured to the rotary table, jaws pivotally secured to said arms to engage the length of pipe above said coupling ring, a flexible element passed around said length of pipe and secured to said arms, and means to rotate said rotary table, substantially as shown and described.

15. 15. In combination with a rotary table for drilling wells having a central opening, and a drill stem mounted in said opening consisting of lengths of pipe connected together by coupling rings, a cylindrical structure mounted in the opening in the table and surrounding the drill stem, means to hold said cylindrical structure stationary, means secured to said cylindrical structure to hold one of the coupling rings, arms removably secured to

the rotary table, jaws pivotally secured to said arms to engage the length of pipe above said coupling ring, a post projecting above each jaw, claws formed integral with each arm, a chain passed around the length of pipe and one of said posts and secured to the claws, and means to rotate said rotary table, substantially as shown and described.

16. In combination with a rotary table for drilling wells having a central opening, and a drill stem mounted in said opening consisting of lengths of pipe connected together by coupling rings, a cylindrical structure mounted in the opening in the table and surrounding the drill stem, hooks pivotally secured beneath said rotary table and engaging said cylindrical structure to hold it stationary, the upper portion of said cylindrical structure formed with a horizontal table, a length of chain passed around the coupling ring and secured to the table, arms removably secured to the rotary table, jaws pivotally secured to said arms to clamp the length of pipe above the coupling ring, posts extending from the upper side of said jaws, claws formed integral with said arms, a length of chain passed around said length of pipe and one of the posts and secured to said claws, and means to rotate said rotary table, substantially as shown and described.

In testimony whereof I hereto affix my signature in the presence of two witnesses.

HARRY R. DECKER.
